Patented Nov. 11, 1919.

UNITED STATES PATENT OFFICE.

JAMES R. BARNARD, OF DENVER, COLORADO.

WINDOW-SHADE.

1,321,587.

Specification of Letters Patent.

Patented Nov. 11, 1919.

Application filed July 17, 1917. Serial No. 181,076.

To all whom it may concern:

Be it known that I, JAMES R. BARNARD, a citizen of the United States, residing at Denver, in the county of Denver and State 5 of Colorado, have invented certain new and useful Improvements in Window-Shades, of which the following is a specification.

This invention relates to window-shades and its primary object resides in providing 10 a shade of simple and durable construction which by readily effected adjustments may be raised or lowered to cover or uncover any portion of a window to which it is applied, without the use of rollers or other 15 winding devices.

I attain this object by the use of a shade composed of a series of lapping slats which are interconnected by flexible tapes to permit of their sliding upon each other for the 20 purpose of folding the shade while it is being raised or lowered.

The flexible bands are attached at their lower ends preferably through the medium of the lowermost slat, to a holder adapted 25 to receive the slats in their folded condition.

A cord fastened to the uppermost slat of the shade is trained over a series of pulleys or other suitable guiding devices at the top 30 of the window-frame to raise the upper end of the shade, and a pair of cords attached to the holder are likewise trained over pulleys at the upper end of the window-frame for the purpose of raising the lower end of 35 the shade when it is desired to uncover the bottom portion of the window.

Cleats fastened at opposite sides of the window are provided to attach the cords for the purpose of securing the shade in its 40 adjusted positions.

An embodiment of my invention is illustrated in the accompanying drawings in the various views of which like parts are similarly designated, and in which—

45 Figure 1 is a face view of my improved window-shade in its operative position in front of a window,

Fig. 2, a section taken along the line 2—2, Fig. 1,

50 Fig. 3, an enlarged sectional view of the holder at the lower end of the shade,

Fig. 4, a transverse section through two of the interconnected slats of which the shade is composed.

Fig. 5, a sectional view of the slats showing their relative positions when bunched within the holder, and

Fig. 6, a longitudinal section through a portion of one of the slats to better show the construction of the clips by which they are fastened to the tapes.

The reference character 2 designates the frame and 3 the sash of a window of ordinary construction.

My improved shade is composed of a series of oblong slats 4 made of cardboard, wood or any other suitable substance and interconnected by two parallel tapes 5 of webbing or other flexible material.

The slats are secured to the tapes by means of normally U-shaped clips 6 which embrace the tapes with their ends passing through openings in the slats at opposite sides of the tapes and bent against the back of the same.

The upper slat of the series is reinforced along its upper edge by a strip 7 of wood or other suitable material and the lower slat of the shade is rigidly secured to the holder 8 in which the slats are received when either the upper end of the shade is lowered or the lower end of the same is raised.

The holder in its preferred form as shown in the drawings, is composed of two U-shaped stirrups 9 rigidly connected by two parallel bars 10 preferably made of wood.

The lowermost slat of the shade is rigidly fastened to the holder by bending the ends of the forward portions of its U-shaped members over and upon the upper edge thereof, as best shown in Fig. 3 of the drawings.

The adjustable suspension of the shade in front of the window-sash is effected through the medium of a number of pulleys which are attached to the upper transverse portion of the window-frame.

These pulleys may be of any convenient construction suitable for the purpose and if used in connection with shades of small dimensions they may consist of screw eyes such as have been shown in the drawings.

A cord 12 fastened in the middle of the reinforcing strip of the upper slat is trained over pulleys 13 and 14 and normally fastened to a cleat 15 applied to the window-frame at a side of the window.

A pair of cords 16 are fastened to the upper ends of the rearmost arms of the U-shaped members of the holder 8 and trained over pulleys 17, 18 and 19.

5 The two ropes are united at a point 20 and normally attached to a cleat 21 at the side of the window opposite to that at which the first-mentioned cleat is fastened.

10 A knot or button at the point of juncture of the two cords is provided to limit the downward movement of the shade and thereby prevent the holder at its lower end from striking the window-sill.

15 By fastening the cords at the upper ends of the rearward arms of the stirrups 9, the holder is compelled to tilt forwardly as clearly shown in Figs. 2 and 3 in which position it is best adapted to receive the slats of the shade without binding and 20 without wear of the tapes by which they are interconnected.

25 In the operation of my invention, the upper end of the shade may be lowered by unfastening the cord from the cleat and permitting the slats to fall by their own weight.

30 The lower slats of the series successively enter the holder in which they are folded together in the position illustrated in Fig. 5, it being observed that the lower portions of 35 the flexible tapes are by the sliding movement of the slats bent across the upper edges of the next adjoining ones without slack or friction.

35 The U-shaped stirrups of the holder are of sufficient capacity to contain all of the slats of the shade in its folded condition so that if so desired, practically the entire window may be uncovered.

40 To subsequently raise the upper end of the shade, the cord 12 is pulled downwardly to exert an upward pull on the uppermost slat of the series which causes the slats contained in the holder to successively move 45 out of the same and reassume their lapping position relative to the next adjoining slats by the extension of the tapes.

When it is desired to raise the lower end 50 of the shade, the united cords 16 are unfastened from the cleat 21 and pulled downwardly to effect an upward movement of the holder.

The slats are as in the first-described movement compelled to enter successively

55 into the holder in which they are folded together face-to-face as before.

When the lower end of the shade is lowered to its full extent, the knot at the juncture of the two ropes will by engagement with the screw-eye 19 prevent the holder 60 from forcibly engaging the window-sill.

Having thus described my improved window-shade in the best form at present known to me, I desire it understood that variations in the details of construction or 65 the arrangement of the parts thereof, may be resorted to within the spirit of my invention as set forth in the following claims:

1. In combination, a collapsible window-shade, a holder fastened at an end thereof and adapted to receive the shade in its collapsed condition, and means for moving the holder relative to the opposite end of the shade. 70

2. In combination, a collapsible window-shade, a holder fastened at an end thereof and adapted to receive the shade in its collapsed condition, and means for moving the opposite end of the shade and the holder 80 with relation to each other. 75

3. In combination, a collapsible window-shade and a holder fastened at an end thereof and composed of connected substantially U-shaped stirrups adapted to receive 85 the shade in its collapsed condition.

4. A window-shade comprising a series of lapping slats, and transversely extending flexible tapes which are fastened to the slats at distances from one of the longitudinal 90 edges thereof, which permit of their folding across the edges of the next adjoining slats when the slats are moved upon each other.

5. A window-shade comprising a series 95 of lapping slats, and transversely extending flexible tapes which are fastened to the slats at distances from the lower edges thereof, which permit of their folding across the upper edges of the next adjoining 100 slats when the slats are moved upon each other.

In testimony whereof I have affixed my signature in presence of two witnesses.

JAMES R. BARNARD.
